UNITED STATES PATENT OFFICE.

GEORGE C. PARK, OF ANADARKO, OKLAHOMA.

SILO-PACKER.

1,111,610.

Specification of Letters Patent. Patented Sept. 22, 1914.

Application filed December 6, 1913. Serial No. 805,032.

To all whom it may concern:

Be it known that I, GEORGE C. PARK, a citizen of the United States, and a resident of Anadarko, in the county of Caddo and State of Oklahoma, have invented a new and Improved Silo-Packer, of which the following is a full, clear, and exact description.

My invention relates to a means for packing ensilage in silos and more particularly to a construction in which a packer device is suspended in the silo from the roof thereof and arranged to be rocked vertically by an operator in the silo and to be raised and lowered, as well as turned about a vertical axis in order to variously position the packer elements in the silo.

The invention consists in the novel features hereinafter particularly described and defined in the claims.

Reference is to be had to the accompanying drawings, forming a part of this specification, in which similar characters of reference indicate corresponding parts in all the views, and in which—

Figure 1 is a vertical sectional view, showing my improved packer applied to a silo; Fig. 2 is a plan view of the packer device, the suspension means being omitted and the silo being shown in horizontal section; and Fig. 3 is a plan view of the overhead tracks and carriage for the suspension means, parts being broken away.

The device is more particularly intended for use in connection with a cylindrical silo A of any improved construction, for packing the ensilage indicated by the letter B.

To the rafters a, of the roof or other overhead part of the silo, brackets 10 are secured and support at their lower ends, a circular track 11, which may be formed of metal tubing. On the track 11, a transverse track 12 is mounted to turn, being provided with running wheels 13, traveling on the annular track. The transverse track 12 is held against displacement by means connecting centrally with the roof, the means shown comprising a hub or enlargement 14 on the said track, provided with an eye 15, the piece of rope 16 or the like serving to connect the eye 15 with the overhead eye 17 on the roof.

A carriage 18 is mounted to travel on the transverse track 12, being provided with a running wheel 19 and suspension means are

provided on the carriage for suspending a packer device as hereinafter described. In the present example, the suspension means comprise a block and tackle, there being a standing block 20 on the carriage 18, a fall block 22 and a rope 21 rove through the said blocks, the rope being made fast in any adjusted position as at 21a.

The suspension device consists of a balance arm 23 having a hook 24 between the ends thereof, preferably at the center, engaging the hook 22a of the fall block 22, said hook 24 being pivoted as at 25 to the balance arm to permit the latter to rock in the vertical plane. Carried by the balance arm at the ends thereof, are packer weights 27 suspended by suitable pivotal connections 28 from the arm. At each side of the pivot 25, the arm 23 is provided with hand holds or grips 26.

With the described construction, the operator standing on the ensilage B as it accumulates and initially on the bottom of the silo, may, by taking hold of one or other of the grips 26, turn the balance arm 23 with the weights thereon about a vertical axis to variously dispose the weights over different portions of the ensilage and may rock the said arm vertically to cause the weights to pack the ensilage. The operator also by reason of the transverse track can give the balance arm and weights a transverse movement and similarly by reason of the annular track may turn the transverse track, causing its wheels 13 to travel on the track 11. Thus the turning of the horizontal track further provides for the turning of the weighted arm about a vertical axis in addition to the turning movement of the arm permitted by the flexibility of the rope 21.

Having thus described my invention, I claim as new and desire to secure by Letters Patent—

1. A packing means for silos, comprising a balance arm, packer weights carried by said arm, and means for supporting said arm at different heights in a silo.

2. A packing means for silos, comprising a vertically rockable arm pivoted intermediate its ends, weights pivoted to said arm, and means for suspending said arm in the silo.

3. A packer means for silos, comprising a weighted packer device, suspension means for the said device, a carriage for the sus-

pension means, and a transverse track for the carriage.

4. A packer for silos, comprising a packer arm, having weights at the ends, suspension means for the said arm, a carriage for the suspension means, a transverse track for the carriage, and a circular track on which the transverse track is mounted to turn.

10 5. A silo packing means, comprising an arm pivoted to rock in the vertical plane,

a packer weight on the arm, and means for suspending the said arm and permitting a turning of the same in a lateral direction.

In witness whereof I have signed my 15 name to this specification in the presence of two subscribing witnesses.

GEORGE C. PARK.
